RIFLESCOPE

Donald J. Burris, Aurora, Colo., and John L. Maulbetsch, Northampton, Mass., assignors to Outdoor Sports Industries, Inc., Denver, Colo.

Filed Mar. 6, 1970, Ser. No. 21,761

Term of patent 14 years

Int. Cl. D16—06

U.S. Cl. D57—1

FIG. 1 is a top plan view of the riflescope showing our new design;

FIG. 2 is a right side elevation thereof;

FIG. 3 is a rear end view;

FIG. 4 is a front end view;

FIG. 5 is a section taken along 5—5 of FIG. 1;

FIG. 6 is a fragmentary left side elevation of the center section; and,

FIG. 7 is a fragmentary bottom plan view of the center section.

The front and rear end portions would appear in FIG. 6 just the same as in FIG. 2 and in FIG. 7 the same as in FIG. 1.

The new design is characterized by the flattened oval shapes of both the front and rear ends as shown in FIG. 3 and 4.

We claim:

The ornamental design for a riflescope, as shown and described.
